RAZOR

Anthony Piotrowski, Chicago, Ill.

Application January 15, 1945, Serial No. 572,934

1 Claim. (Cl. 30—70)

1 This invention relates to improvements in safety razors.

An object of this invention is the provision of improved means for the mounting of a flexible blade upon a safety razor.

A further object of this invention is the provision of an improved safety razor with guard means by which to prevent cutting of the skin during shaving; the blade being so mounted as to permit the efficient disposal of hair and shaving cream.

Other objects and advantages of the invention will be apparent from the following detailed description.

In the accompanying drawings, forming a part of this specification, and wherein similar reference characters designate corresponding parts throughout the several views—

Figure 1 is a plan view of an improved blade structure.

Figure 2 is a plan view of the under side of the head structure of the safety razor showing an improved guard plate.

Figure 3 is a cross sectional view thru the head structure of the modification shown in Figure 2; the view being taken substantially on the line 3—3 of Figure 2, with a handle shown mostly in elevation.

The safety razor structure includes a handle 10 with one end portion 11 provided with a shank 12 preferably having an annular flange 13 which cooperates with an internal flange 14 of a clamping nut 15 to provide a union connection. The nut 15 has a finger engaging externally knurled flange 16 and is internally screw threaded at 17 for detachable connection upon a screw threaded shank 21 of the top plate 20. There is a polygonal (as square) cross sectional socket 18 in the shank 12 at the base of the screw threads 17.

The top plate 20 is rectangular in plan and transversely curved as shown in Figure 3. Centrally of the concaved side a shank 21 is provided, integral therewith. The shank 21 at its outer end has a square or polygonal cross sectioned reduced extension 22 adapted to fit in the polygonal cross sectioned socket 18, which of course cooperates in preventing turning movement of the top plate when it is located upon the shank 12. The top plate 20 is provided at opposite sides of the shank 21, along its longitudinal axis, with elongated tapered bosses 23 and 24.

A blade structure 25 is provided having a flexible body portion 26 provided with a circular central opening 27 and the elongated end openings 28. The body portion 26 is provided at the

2 marginal edges thereof with non-flexible hardened cutting strips 29 which may be welded or otherwise secured to the flexible body portion 26. This provides a blade having a hardened cutting edge which may be resharpened, whereas the flexible body portion 26 may be made of relatively inferior steel.

The guard plate 30 shown in Figures 2 and 3, is of transverse concavo-convex cross section, being outwardly convex, including circular and end elongated openings for receiving the screw shank 21 and end bosses 23 and 24 respectively of the guard plate.

The guard plate 30 is provided at its outer marginal edges with a continuous guard portion 31 each having next adjacent thereto and inwardly thereof a longitudinally-extending groove 32 (see Figure 3) over which the cutting edge of the blade lies; the guard margins 31 defining convex surfaces 33 beyond the groove 32. The material of the guard plate 30 along the groove 32 and extending partly into the convex surface 33 and inwardly toward the longitudinal center of the guard plate beyond the groove 32 is provided along each marginal edge with a series of elongated openings 35 for the passage of debris during the shaving operation. Between the openings 35 there are located along each margin of the guard plate a series of bosses or projections 36, extending outwardly from its outer face 37, upon which the blade body portion 26 is adapted to lie. In this manner the blade does not contact any other portion of the guard plate but these projections, yet it may be flexed as will be perfectly apparent from Figure 3.

In assembly, the blade 25 is conventionally associated with the top plate 20, both are disposed upon the guard plate 30 with the free end of the shank 21 in the mouth of the nut 15 and the latter is then rotated to cause coupling of the parts, as is now obvious.

As may be seen in Figure 3, the grooves 32 underlie the cutting strips 29 and their edges, and the openings 35 extend from and partly through the guard portions 31, through the grooves 32 and toward the longitudinal center of the guard plate.

The parts of the razor, other than the blade, may be made of some light material, such as aluminum or one of its alloys.

From the foregoing description of this invention it is apparent that I have provided an efficient safety razor so arranged that the parts are accessible and efficient and clean shaving may be facilitated.

Various changes in the shape, size and arrange-

inent of parts may be made to the form of invention herein shown and described, without departing from the spirit of the invention or the scope of the following claim.

I claim:

In a safety razor provided with a flexible blade, said safety razor including a rectangular outwardly convex guard plate having an outer face, a longitudinally-extending marginal edge, and a longitudinally-extending guard portion extending 10 from said marginal edge toward the longitudinal center of said plate, said guard portion being outwardly convex, said guard plate have a longitudinally-extending groove inwardly of and next adjacent said guard portion, said groove being 15 constructed and arranged to underlie a cutting edge of said blade, and said guard plate being provided with a plurality of spaced-apart longitudinally-extending openings extending through 20 said guard plate from and partly through said guard portion, through said groove and toward the longitudinal center of said guard plate, and

a plurality of blade-supporting bosses between the ends of adjacent openings and extending outwardly of said outer face.

ANTHONY PIOTROWSKI.
